UNITED STATES PATENT OFFICE.

JOSEPH HORNIK AND JACOB TRAUTNER, OF MILWAUKEE, WISCONSIN.

STREET-INDICATOR.

1,315,501.

Specification of Letters Patent. Patented Sept. 9, 1919.

Application filed February 19, 1918. Serial No. 218,083.

To all whom it may concern:

Be it known that we, JOSEPH HORNIK and JACOB TRAUTNER, citizens of the United States, and residents of Milwaukee, in the 5 county of Milwaukee and State of Wisconsin, have invented certain new and useful Improvements in Street-Indicators; and we do hereby declare that the following is a full, clear, and exact description thereof.

10 Our invention relates to new and useful improvements in indicators for use on street cars and the like, particularly those which are used to successively indicate streets or stations at which the car is to stop.

15 The principal object of our invention is to improve upon the construction and operation of devices of this character whereby such construction may be simplified, the operation rendered more efficient, and the cost 20 of the same materially reduced.

An additional object is to provide a simple means for retaining the sign carrying sheet or curtain taut.

25 A still further object is to provide an arrangement for effectively feeding the flexible sheet or curtain from one carrying roller to the other and back again.

An additional object is to provide means 30 for feeding the flexible sheet or curtain step by step from one carrying roller to the other.

With these and other objects in view the invention resides in the novel features of construction, combination and arrangement 35 of parts which will be hereinafter more particularly described and claimed and shown in the drawings, wherein:

Figure 1 represents a vertical longitudinal sectional view taken substantially on the 40 plane of the line 1—1 of Fig. 2.

Fig. 2 is an end elevational view of our invention, and

Fig. 3 is a vertical transverse sectional view taken substantially on the plane of 45 the line 3—3 of Fig. 1.

In the preferred embodiment of our invention the flexible sheet or curtain 1 on which the street or station names are painted or stamped is inclosed in a sheet metal casing 2 having a horizontally elongated opening 3 in its front wall through which street or station names are visible, said opening 50 preferably being closed by means of a transparent panel 4 of glass or the like. Arranged within the casing 2 so that the flexible sheet 1 is disposed between it and the

opening 3 is an electric light bulb or other source of illumination 5.

The end walls of the casing 2 carry bearings for a pair of spaced superimposed 60 shafts 6 and 7, one end of the shaft 6 being extended beyond the adjacent end of the casing as at 6', said shafts each having a roller loosely mounted thereon, the roller carried by the shaft 6 being designated by 65 the numeral 8 and that on the shaft 7 by the numeral 9. The flexible name carrying sheet 1 is adapted to have its opposite end portions wound around these rollers as shown in Fig. 2, said sheet being also trained 70 about a rubber faced feed roll 10 mounted on a shaft 11 which also projects through one end wall of the casing, and an idle roller 12. If necessary an additional idle roller 13 may be employed.

75 Although each of the rollers 8 and 9 are free to move independently of its supporting shaft, the same are preferably connected thereto by coiled springs 14. As shown in Fig. 1 each of these springs surrounds one 80 of the shafts and has one end secured thereto, the opposite end being connected to the adjacent roller. The shafts 6 and 7 are in turn connected so that they are rotated in unison by means of a pair of spur gears 85 15 and 16, the teeth of which are continually enmeshed.

As hereinbefore mentioned the name carrying sheet is fed from one roller 8 or 9 to the other by means of the feed roll 10. 90 The latter is revolved by the rotation of a gear 17 loosely mounted on the portion 6' of the shaft 6 and a pinion 18 keyed to the projecting end of the shaft 11. This gear 17 and the pinion 18 are preferably disposed upon the outer side of the casing 2 while the parts hereinbefore described are all inclosed therein.

The gear 17 is rotated in either direction and in step by step motion by the operation 100 of a bell crank lever 19, which is also loosely mounted on the portion 6' of said shaft 6. One arm of the bell crank carries a pawl 20, the end of which engages any one of the series of stops 21 carried by the gear 17. 105 From Fig. 2 it will be noted that this pawl may be swung to either one of two positions whereby it may engage either side of the stops 21 to thus intermittently rotate the gear 17 in either direction. The bell crank 110 is obviously rocked by the reciprocation of a pull rod 22 one end of which is pivoted to

one arm of the bell crank while its other end portion is cylindrically reduced and slidably disposed in a stationary guide 23. An expansion coiled spring 24 surrounding 5 the reduced portion has one end engaged with the guide 23 and its opposite end with the shoulder formed by the reduced portion. Thus by pulling downwardly on the rod the bell crank will be rocked and the pawl, when 10 in the full line position shown in Fig. 2, will engage one of the stops 21 so that when said rod is released the spring 24 will return it to the position shown in said figure to thereby rotate the gear 17 in a counter-clockwise direction. When the pawl is 15 swung to the dotted line position shown in Fig. 2 it will be obvious that the gear will be rotated in a clockwise direction and that one of the stops will be engaged upon the 20 downward movement of the rod, the spring 24 being merely used to return the parts to their inoperative positions. A detent 25 carried by the rod 22 engages between certain of the teeth of the gear 17 when the 25 parts are in their inactive positions to thus prevent the same from accidental movement.

The operation of the invention is substantially as follows: After the flexible sheet 1 has had its opposite ends connected 30 to and wound upon the rollers 8 and 9, the tension of the springs 14, both of which are coiled in the same direction, may be increased by revolving the shaft 6 in a clockwise direction, the shaft 7 being rotated 35 simultaneously therewith and to the same extent owing to the gear wheels 15 and 16. The feed roll 10 may now be revolved step by step by pulling upon the rod 22 as hereinbefore mentioned. Assuming that the flexible sheet 1 is to be wound off of the roller 8 and on to the roller 9, it will be seen that 40 at practically no time during this movement will the rollers be moving the same amount owing to the differences in number of thicknesses of the sheet which is wound thereon. Thus when the roller 9 is just beginning to 45 receive the sheet it will move at a greater rate of speed than the other roller 8, whereas when the last mentioned roller has been 50 nearly emptied it will revolve at a higher rate of speed than the other. The tension of the springs 14 would thus be continually varying if it were not for the fact that the shafts 6 and 7 are connected together and 55 must revolve at the same rate of speed. This connection therefore compensates for the differences in the amount of movement of the rollers 8 and 9 and retains the tension of the springs so nearly constant that under

no conditions will there be any slack in the 60 flexible sheet 1, but on the other hand the end portions of said sheet will be tightly wound on said rollers.

When the flexible sheet is to be wound from the roller 9 on to the roller 8, as for 65 instance when the car reaches the end of its trip, the pawl is shifted to the side of its arm of the bell crank 19 opposite to that to which it formerly projected. The flexible sheet may be quickly wound from one 70 roller to the other without the use of the step by step mechanism by revolving the gear 17 by a socket wrench 26 which is disposed over the hub 27 of said gear.

Various minor changes may be made in 75 the form and proportion of the several parts of our invention without departing from the principles thereof. In other words although the device illustrated is adapted to be placed on the inside of a street car or the 80 like and actuated by pulling upon the rod 20, it is obvious that the same might be slightly changed and disposed upon the outer side of a car as a destination indicator. 85

We claim:—

1. An indicator of the class described including a pair of shafts, intermeshing gears on said shafts, a pair of rollers, a spring connecting each roller and a corresponding 90 shaft, a feed roller at one side of one of the first named rollers, a shaft for said feed roller, means for procuring step rotation of the feed roller shaft, a web wound about the first named roller adjacent the feed 95 roller and extended from the inner portion of the roller at its side adjacent the feed roller and trained about the feed roller and then trained about the other first named roller, meeting said roller at its outer portion. 100

2. An indicator of the class described including a pair of rollers, a drive roller, a web wound on the first named rollers and trained about the drive roller, a shaft for the drive 105 roller, a pinion on the shaft, a loosely mounted gear wheel meshing with the pinion, ratchet stops on the peripheral portion of the pinion, a movable pawl successively engageable with said stops to procure 110 successive step rotations of the gear wheel, and means for moving said pawl.

In testimony that we claim the foregoing we have hereunto set our hands at Milwaukee, in the county of Milwaukee, and 115 State of Wisconsin.

JOSEPH HORNICK.
JACOB TRAUTNER.
